UNITED STATES PATENT OFFICE.

MARTHA A. TIENKEN, OF NEW YORK, N. Y.

HAIR-WAVING DEVICE.

Application filed July 21, 1928. Serial No. 294,516.

This invention relates to a device for waving or marcelling hair.

The principal object of the invention is the provision of a device of the indicated character embodying novel features of construction and operation, whereby waves may be produced in the hair which will be well defined and lasting, and without injury or tearing the hair.

10 The nature of the invention and its distinguishing features and advantages will appear when the following specification is read in connection with the accompanying drawing, in which—

15 Figure 1 is a side elevation of the device shown open.

Fig. 2 is a side elevation of the device closed, and parts being broken away to show certain features.

20 Fig. 3 is a plan view of the device shown closed.

Fig. 4 is a sectional view taken approximately on the line 4—4 of Fig. 2, and looking in the direction indicated by the arrows.

25 Referring now more particularly to the several views of the drawing, it will be apparent that, the device includes a pair of lever members 10 and 11 which are connected with each other for relative pivotal movement by a pivot 12. Each of the lever members 10 and 11 has a handle 13. The lever member 10 has rigidly connected therewith a plurality of waving members 14 and 15. Each of the waving members 14 is in the form of a channel, the same being substantially of U-shape in cross section, and each of said members 14 is provided with a longitudinal slot 16. The said waving members 14 are connected together in spaced and parallel relationship by

30 members 17, respectively extending across the opposite ends thereof and secured to portions of the members 14 in any suitable manner. The lever member 10 is provided with angular portions which are respectively connected with the member 17, as at 18. The waving members 15 are of similar shape, each being substantially J-shaped, and are respectively disposed at opposite sides of the group of waving members 14, and are also attached at

35 the opposite ends to said members 17. The lever member 11 has connected therewith transversely thereof a cross bar 19 with which are connected a plurality of hair waving members or irons 20. One end of each of the waving members or irons 20 is rigidly connected with the bar 19, and said irons 20 are disposed

in spaced and parallel relationship, and are adapted to move between the waving members 14 and 15 to cooperate therewith to produce simple waves in the hair.

60 In order to convert the simple waves of the hair produced by the waving members 14, 15 and 20 into compound or Marcel waves, there is provided means which is operated by the movement of the lever members 10 and 11. 65

The said means includes pairs of hair engaging elements 21 and 22. Each of the elements 21 and 22 is in the form of a comb presenting teeth 23. The pair of elements 21 are connected together by a cross piece 24, and the pair of elements 22 are connected together by a cross piece 25. The pair of elements 21 are associated respectively with a pair of the hair waving members 14, the teeth of each element extending downwardly through the 70 slot 16 of the related member 14. The other pair of elements 22 are similarly associated with the other two waving members 14, and the teeth 23 of each of these elements extending downwardly through the slot 16 of the 75 related member 14, as shown most clearly in Fig. 4. Each of the elements 21 and 22 is provided with pins 26 near the opposite ends thereof which slide in contact with the related member 14. Longitudinally disposed members 27 having the opposite ends thereof respectively connected as at 28 with the member 17 prevent relative upward movement of the elements 21 and 22 with respect to the waving members 14, while the pins 26 prevent relative downward movement of said elements.

80 The cross piece 24 has a lug 29 with which one end of a member 30 is pivotally connected as at 31, and the opposite end of said member 30 is pivotally connected as at 32 with a member 33 pivotally connected with the lever member 10, as at 34. The cross piece 25 has rigidly secured thereto an upstanding member 35, the upper end of which is pivotally connected as at 36 with one end of a member 37, the opposite end of which is pivotally connected as at 38 with the member 33. The lever member 11 has an arm 39. A link 40 has one end thereof connected with the arm 39 by a pivot 41 which may be disposed in any 85 one of the holes 42 in said arm. The opposite end of the link 40 has a longitudinally disposed slot 43 which accommodates a pivot 44 on the member 37. The arrangement of the parts is such, that when pressure is applied 90 to the handles 13 to move the waving members or irons 20 toward the waving members 14

120

and 15, the elements 21 and 22 will be moved relatively to their related waving members 14, the elements 21 being moved forwardly, and the elements 22 being moved rearwardly 5 while engaged with the strands of the hair, just prior to the clamping engagement of the waving members 14, 15 and 20 with the strands of the hair. It will therefore be understood that the waving members 14, 15 10 and 20 will produce simple waves in the hair, while the elements 21 and 22 will further wave the hair to produce the well known marcel effect. The side portions of the waving members 14 and 15 will be flexible to some 15 extent, and as a consequence the waving members or irons 20 will cooperate therewith to effectually crimp or crease the strands of hair, to the end that the waves in the hair will be well defined and lasting. By imparting relative separating movement to the handles 13, 20 the device may be readily disengaged from the hair without in any way deforming the waves produced.

It is to be understood that the invention is 25 not restricted to the precise arrangement of parts shown and described, as details of construction may be modified and rearranged without departing from the spirit of the invention, the scope of which is limited only by 30 the terms of the appended claims.

I claim:

1. A hair marcelling device comprising waving members, said waving members consisting of a group of interconnected cross 35 sectionally convex members arranged side by side and a second group of interconnected relatively spaced members which move between and cooperate with the first group of members, means connecting the groups of 40 waving members together for movement toward and away from each other, groups of hair engaging members respectively associated with and projecting through the convex waving members for relative longitudinal 45 movement, means to move said groups of waving members toward and away from each other, and means operated by the operation of the last mentioned means to move the groups

of hair engaging members relatively in opposite directions. 50

2. In a hair waving device, a group of interconnected spaced hair waving members each of which is substantially of U-shape in cross section and provided with a longitudinal slot, elements respectively associated with said waving members and each having hair engaging members which project through the slot in the related member, a second group of interconnected spaced hair waving members which cooperate with the first group to wave 60 the hair when brought into clamping engagement therewith, lever means connecting the groups of waving members together for relative movement, means connecting groups of said elements together, and means actuated by 65 the lever means in response to the actuation of the latter to move said groups of elements in relatively opposite directions, just prior to the full engagement of the waving members with the hair. 70

3. In a hair waving device, a pair of arms pivotally connected together, a group of waving members rigidly connected with one of said arms side by side and each having a convex surface, a second group of spaced waving members rigidly connected with the other arm, one group of waving members cooperating with the other group of waving members to wave the hair when brought into clamping engagement therewith by actuating said arms, hair engaging members respectively associated with and projecting through the convex surface of a plurality of the waving members of one group, and means connecting said hair engaging members together in independent groups, and means connected with said arms and the last mentioned means to move the groups of hair engaging members relatively in opposite directions by the movement of said arms to compound the waves in the hair 80 produced by said waving members. 85

Signed at New York in the county of New York and State of New York this 19th day of July, A. D. 1928.

MARTHA A. TIENKEN.
